GAS STOVE

Filed Jan. 14, 1922

Patented July 22, 1924.

1,502,200

UNITED STATES PATENT OFFICE.

WILLIAM T. HOWLETT AND HENRY O. SMITH, OF NEW YORK, N. Y.

GAS STOVE.

Application filed January 14, 1922. Serial No. 529,127.

To all whom it may concern:

Be it known that we, WILLIAM T. HOWLETT and HENRY O. SMITH, both citizens of the United States, and residents of New York, in the county of Kings and State of New York, have made a certain new and useful Invention in Gas Stoves, of which the following is a specification.

This invention relates to gas stoves, and 10 has for its primary object the provision of a gas stove which is simple in structure, economical of manufacture, and economical and efficient in operation.

A further object of the invention is to 15 provide a gas stove which relies upon circulation of heated air entirely for its efficient operation, as distinguished from heat radiation, with the incident advantages of safety, economy in gas consumption, and 20 more efficient and greater distribution of heat for any given period of time.

A further object of the invention is to 25 provide a gas stove of the character hereinbefore set forth wherein effective thermo insulation is obtained for the sides of the stove whereby the same remain cool irrespective of the time of operation thereof, thereby eliminating great sources of danger 30 of stoves of this nature both for conflagration or burns due to incidental or other contact with the sides of a stove when in use.

A further object of the invention is to 35 employ the principle of the Bunsen burner in connection with a stove of this nature, and to employ in connection therewith a maximum amount of draft to effect heating air currents and thereby secure heat by circulation as distinguished from the ordinary 40 gas stove structure which is designed either to heat an area of the stove itself and thereby by effect heating through radiation, or to heat by radiation and circulation.

A further object of the invention is to 45 provide means in connection with the utilization of the Bunsen burner principle for rendering the same substantially noiseless in operation.

Further objects of the invention will appear more fully hereinafter.

The invention consists substantially in 50 the construction, combination, location and relative arrangement of parts all as will be more fully hereinafter set forth, as shown by the accompanying drawing and finally 55 pointed out in the appended claims.

Referring to the drawing,—

Fig. 1 is a view in section of a gas stove embodying our invention;

Fig. 2 is a sectional view taken on the line 2—2 of Fig. 1, and looking in the direction 60 of the arrows; and

Fig. 3 is a similar view taken on the line 3—3 of Fig. 1, and looking in the direction of the arrows.

The same part is designated by the same 65 reference character wherever it occurs throughout the several views.

As hereinbefore briefly outlined, the stove of our invention is directed to utilizing the Bunsen burner principle for heating large 70 currents of air by constantly flowing by a heated area or surface to thereby effect heating by circulation as distinguished from radiation alone, or radiation and circulation. Heating accomplished in this manner 75 is well recognized in the art to be more efficient and more economical than the radiated heat type of stove. The reason for this will be obvious when it is considered that if good circulation is obtained, the heat is 80 more efficiently distributed, and in consequence a greater area and volume can be heated in the shortest possible time. Another disadvantage of the type of stove which radiates heat is that the sides of the 85 stove become extremely hot, frequently resulting in bad burns to children or grown-ups coming in contact therewith, and danger due to fire or due to some inflammable or combustible material coming in contact 90 with the sides of the stove.

We secure the safe feature of our invention by insulating the heated area effectively from the outer surface of the stove.

We will now describe a structure embodying our invention in connection with the illustration thereof contained on the drawing appended hereto, but we wish it to be understood that the structure selected for the purpose of illustration is to be regarded 95 in an illustrative sense and not in a limiting sense, and we do not desire to be limited or restricted to any particular form, shape, size, construction or material, as many modifications and changes in details and arrangements will readily occur to those skilled in the art without departing from the spirit and scope of our invention. In the form shown, however, we show a usual stove structure, preferably cylindrical, with the 100 outer shell 1 thereof of any suitable material, preferably metal, supported by the 105 outer shell 1 thereof of any suitable material, preferably metal, supported by the 110

usual legs 2. The shell 1, if desired, may be provided with an ornamental skirt 3, secured to the bottom part thereof, and is preferably provided with a bottom 4, secured thereto, which bottom 4 is preferably of metal provided with numerous fine perforations therein. The purpose of the perforations is to afford greater air draft, as will be more fully hereinafter set forth, and at the same time afford a bottom to the structure to prevent any material from falling through the bottom of the stove. While this bottom is not strictly required with the gas stove of our invention, it is nevertheless shown, as the same constitutes a requirement in some States as a fire preventive measure. The gas supply is fed through the bottom of the stove in any suitable manner, for example, by means of a pipe 6, which is secured to an angle joint 7, the Bunsen burner structure 8 being likewise secured thereto and projecting upwardly in the shell 1, in the approximate centre thereof. Of course, the pipe supply 6 is provided with means for attachment to a rigid or flexible supply pipe (not shown), and is controlled by the usual or any desired type of stop cock (not shown). The Bunsen burner is of the usual construction, including the air supply 10, and the tip thereof 11 extends well towards the centre of the shell 1. Suitably supported by the shell 1, but spaced therefrom is a metal plate 12, which, in the form shown, is cylindrical.

Any suitable means may be provided for supporting the shell 12 in its spaced relation with reference to the shell 1. We have shown as illustrative of one means, to which, however, we do not desire to be limited or restricted, brackets 13, riveted or otherwise secured at one end to the shell 1, and at the other end to the shell 12. We insulate the metal shell 12 with reference to the shell 1, as efficiently as economy and facility will permit, and have found that the most efficient and economical method of insulating the same is by means of an asbestos covering 14, which completely surrounds the same and is held in place by screws, rivets, bolts or the like. For this purpose the attachment means employed for securing the ends of the brackets 13 may be employed. The shell 12 is of much shorter length than the shell 1, and is positioned relative the tip 11 of the Bunsen burner 8, so that the end of the burner projects in the approximate centre of the shell 12 but a slight distance. In other words, the burner and the shells 12 and 1 are in concentric arrangement with each other, with the shell 12 located at the approximate centre of the shell 1, with the tip 11 of the Bunsen burner 8 projecting upwardly in the shell 12 a short distance. At or near the bottom of the shell 12, we provide suitable means for supporting what

we will term the crucible-shaped radiator. While these means may be of any suitable or desired nature, we have found it sufficient to bolt, screw, rivet or otherwise attach to the shell 12 (and likewise utilize these bolts, etc., to hold the lower edge of the asbestos covering 14 on the shell 12) a plurality of brackets 15 with their ends upturned as at 16, to form flanges to position and retain thereon the crucible shaped radiator 17. The crucible shaped radiator 17 may be of any suitable or desired shape or material. We have found, however, a radiator formed of fire clay open at one end and closed at the other, and provided with numerous perforations 18, therein, for easy flare of gas flame, and positioned in an inverted position over the brackets 15, to be effective for the purpose of this invention. The radiator is spaced from the inner shell 12, as is apparent, and is concentrically arranged relative to the shells 1 and 12 and the burner 8. To prevent injury to the radiator, especially during the shipment thereof, an additional bracket 20 of any suitable material may be provided for engagement with the top of the crucible shaped radiator 17. The top of the stove is provided with a hood 21, which may be of any suitable shape or material. We have found it advisable to make the top 21 separate from the shell 1, and capable of being inserted therein, as one means of securing the two together. The top may be formed in any suitable manner. The sole function thereof is to permit free egress of air from within the shell 1 therethrough. Therefore, the same may be formed of wire mesh, or, as shown, of metal provided with numerous large perforations therethrough. The top may be provided with a removable stopper 22, to permit a pan or the like to be placed thereon for heating purposes, if desired. The bottom of the shell 1, i. e., that portion thereof below the lower edge of the inner shell 12, is provided with a door 23, equipped with any suitable type of lock or catch 24. The door and the entire side portion of the shell 1 is provided with numerous perforations, as indicated, to permit utilizing an exceedingly large draft area.

The operation of the burner thus far described is as follows:

The gas is turned on so that an unobstructed flow to the Bunsen burner is obtained, and a flame is applied to the tip of the burner through the door 23. The heat of the flame, of course, heats the crucible shaped radiator 17 and the inner shell 12, and the space between 12 and 17. At the same time an enormous draft area is provided at the lower portion of the stove, and due to the heat from the burner, the crucible shaped radiator 17, and the inner shell 12, the air passing thereby becomes heated

- through contact therewith, which heated air is augmented, of course, by a portion of the air passing by the burner tip into the crucible shaped radiator and through the perforations thereof, and the air flowing between 1 and 12 becomes mixed with and heated by the heated air. This heated air flows freely through the top or hood of the stove, and naturally seeks the altitude.
- 10 With this construction it will be apparent that the colder air from the bottom of the room is first utilized for heating purposes, and the heated air is circulated, as distinguished from radiation, because due to the outer shell 1 being effectively insulated from the inner shell 12, non-radiation is obtained, with the incident advantages of safety hereinbefore pointed out, while, at the same time, due to the large volume of air handled by
- 15 the stove, the circulation is speeded up, and in consequence the greatest amount of heat is circulated to effect heating in the least amount of time, with the resulting greater efficiency and economy, as above stated.
- 20 The crucible shaped radiator 17, in addition to serving its function of heating, also serves to render the Bunsen burner substantially noiseless in operation.
- 25 Many modifications and changes in details
- 30 will readily occur to those skilled in the art without departing from the spirit and scope of our invention as defined in the claims, but having now set forth the objects and nature of our invention, what we claim as new and

useful and our own invention and desire to 35 secure by Letters Patent is:

1. In a gas heater, an outer shell having a perforated lower area and an unperforated upper area, a perforated bottom for said outer shell, an inner shell supported from 40 said outer shell in spaced relation therefrom, said inner shell extending from said perforated area and terminating in said unperforated area to thereby provide a free air inlet area below said inner shell and a large heat 45 mixing chamber above said inner shell, a radiator supported in spaced relation within the inner shell, and a burner extending into said radiator.
2. In a gas heater, an outer shell having a 50 perforated lower area and an unperforated upper area, a perforated bottom for said outer shell, an inner shell supported from said outer shell in spaced relation therefrom, said inner shell extending from said perforated area and terminating in said unperforated area to thereby provide a free air inlet area below said inner shell, an asbestos covering for said inner shell, a large heat 55 mixing chamber above said inner shell, a 60 crucible shaped radiator supported in spaced relation within said inner shell, and a burner extending into said radiator.

In testimony whereof we have hereunto set our hands on this 12th day of January, 65 A. D. 1922.

WILLIAM T. HOWLETT.
HENRY O. SMITH.
